UNITED STATES PATENT OFFICE.

ROBERT MILLS EVANS, OF SEATTLE, WASHINGTON.

RAILWAY-SWITCH MECHANISM.

Application filed January 30, 1926. Serial No. 84,875.

This invention relates to improvements in railway switch mechanism and more particularly to manually actuated mechanism whereby the tongues of a switch are shifted from one position to another.

It is the principal object of the invention to provide mechanism designed for a double tongue switch, which is easily operated and which permits readjustment of the switch 10 tongues at any time that might be necessary due to shifting of the main track or due to widening of the gauge.

Other objects reside in the various details of construction and combination of parts as 15 is hereinafter described.

In accomplishing these and other objects, I have provided the improved details of construction, the preferred forms of which are illustrated in the accompanying drawings, 20 wherein—

Figure 1 is a perspective view of a switch box and switch actuating mechanism embodied by the present invention.

Figure 2 is a longitudinal sectional view 25 just within the forward wall portion of the box.

Figure 3 is a plan view of the box and switch actuating mechanism.

Figure 4 is a cross section taken on line 30 4—4 in Figure 3.

Figure 5 is a plan view illustrating the location of and method of attachment of switch mechanism of the present character with a double tongue switch.

Referring more in detail to the drawings—

The present device is designed especially for use in connection with railways in pavement and the switch actuating mechanism is contained in a box 1 which is to be set in 40 the pavement between the rails of a track flush with the surface and it is equipped with a top cover 2 attached to the box by hinges 3. In the opposite end walls 4 and 5 of the box are openings 6 and 7 through 45 which rods 8 and 9 are slidably extended and these rods, at their inner ends, are connected, as presently described, to the switch actuating mechanism and at their outer ends are operatively connected to the switch 50 tongues, which in Figure 5 are designated by reference characters T—T and the main track rails are designated at R—R.

Fixed to the back wall 10 of the box midway between the end walls is a strip of angle iron 11 having a horizontally extended top flange 12 beneath which a block 13 is slida-

bly held for movement back and forth in the longitudinal direction of the box. This block in turn is mounted on a base plate 14 which is slidable on the base wall 15 of the 60 box and which at its opposite ends, which extend somewhat beyond the ends of the block and also beyond the ends of the angle iron, has upturned flanges 16, each provided with an upwardly opening notch 17 through 65 which the inner ends of the rods 8 and 9, respectively, are extended; the rods being connected to their respective flanges by means of nuts 18 which are threaded thereonto and tightened against opposite sides of 70 the flanges. The block 13 is limited in its slidable movement in opposite directions on the base plate 14 by means of bolts 19 and 20 which are threaded into the opposite ends of the block with their outer ends disposed 75 in spaced relation to the adjacent flanges 16. These bolts are adjustable into and from the block so as to provide for varying the distance between their ends and the flanges and lock nuts 22 and 23 are threaded onto the 80 bolts against the ends of the block to retain them at adjusted positions.

The switch tongues T—T are moved from one position to another for the purpose of opening or closing the switch, by longitudinal shifting of the base plate 14 to which the rods 8 and 9 are connected. This is accomplished by shifting of block 13, and its shifting means comprises a hand lever 25 normally disposed within the front of the box 90 and adapted to swing in a vertical plane. The lever is connected pivotally near one end to the block 13 by means of a pin 26 that extends horizontally and inwardly through the lever and into the block, and mounted 95 in the adjacent end of the lever is an outwardly projecting stud 28 that is slidable in a vertical groove 29 formed between shoulders 30 and 31 on the inner face of the front wall 32 of the box. At the swinging, or 100 outer end of the lever is a weight 33 for the purpose of carrying the lever downwardly after it has been swung upwardly from one side past the center point. The weighted lever is adapted, when in either functional 105 position, to lie wholly within the switch box so that the cover may be closed down.

It is preferred that the distance between pin 26 and stud 28, and the adjustment of bolts 19 and 20 in the ends of block 13 be 110 such that the distance of movement of the block 13 caused by swinging the lever 25

from one side to the other be approximately twice that of the plate 14.

Assuming that the device is so constructed, in using the same, it is placed centrally of or between the switch tongues with the outer ends of rods 8 and 9 operatively connected to the switch tongues T-T and with their inner ends extended through the openings 6 and 7 and connected to the flanges 16 at the ends of the plate 14. When it is desired to throw the switch from one position to another, the cover 2 is opened and the weighted end of lever 25 is swung upwardly and over the center point and is pushed down into the other end of the box. As the lever is thus swung over, the stud 28 slides downwardly in slot or groove 29 and acts as a fulcrum by means of which the lever, through the connecting pin 26, causes the block 13 to be shifted from one end toward the other end of the box so that the outer end of either the bolt 19 or 20 is brought against the adjacent flange 16 of plate 14 to effect movement of the plate whereby the switch tongues, through connecting rods 8 and 9, are moved.

It is readily apparent that any desired readjustment of the switch tongues with respect to each other may be made by the adjustable connections provided between the flanged ends of the base plate 14 and that any readjustment in distance of movement of the switch tongues that might be required, due to shifting of the track or variation of the gauge may be made by adjusting either one or both of the bolts 19 and 20 into or from the block 13. With this construction the actuating lever 25 may be swung to substantially a vertical position in shifting the switch block before the end of a bolt 19 or 20 comes in contact with a flange 16 and then the work required for shifting the switch tongues may be done by pushing downward on the lever with the foot. The weight 33 assists in carrying the lever down into the box.

Having thus described my invention, what I claim as new therein and desire to secure by Letters Patent, is:

1. In a railway switch mechanism, a housing, a plate shiftable in opposite directions in said housing and adapted for operative connection with switch tongues, a shifting block mounted on said plate and having a lost motion connection therewith which permits limited movement of the block in opposite directions and a switch actuating lever having operative connection with the housing and with the block whereby the latter may be shifted to effect movement of the plate.

2. In a railway switch mechanism, a housing, a plate shiftable in opposite directions in said housing and having operative connec-

tion with switch tongues, a shifting block 65 shiftable on said plate in opposite directions corresponding to movement of the plate, and adjustable means for limiting the movement of the block on the plate in either direction and through which an operative connection 70 between the block and plate is effected and a switch actuating lever operatively connected with the housing and with the block whereby the latter may be shifted to effect movement of the plate.

3. In a switch mechanism of the character described, a switch box provided with a wall slot, a plate shiftable longitudinally in the box and adapted for operative connection at its ends with switch tongues, a block 80 shiftable a limited distance in opposite directions on said plate and by means of which said plate may be shifted and a switch actuating lever having a stud at one end pivotally shiftable in the said slot and having a 85 pivot pin connection with the block whereby movement of the lever from one position to the other effects shifting of the block and a resultant movement of the plate.

4. In a railway switch mechanism, a 90 switch box provided with a vertical slot in a side wall, a plate mounted for longitudinal shifting in the box and having flanges at its opposite ends, switch tongue actuating rods connected with said flanges, a block longitudinally shiftable on the plate, bolts adjustably mounted in the opposite ends of the block for engagement with said flanges to limit its shiftable movement, a switch lever having a stud at one end pivotally shiftable 95 in the said slot and having a pivot pin connection near said stud with the said block whereby the latter may be shifted to effect operative movement of the plate.

5. In a double tongue switch mechanism, a switch box having openings in its end walls and provided with a vertical slot in a side wall, a plate mounted shiftable on the base of the box for movement longitudinally thereof, said plate having upturned flanges 100 at its end, switch tongue actuating rods shiftable through said end wall openings and adjustably connected at their ends to the said plate flanges, a block shiftable mounted on the plate for movement longitudinally 105 thereof, bolts adjustably threaded into the ends of the block to limit its shiftable movement with respect to the plate, and adapted to be engaged with the end flanges of the plate to effect its movement, a switch lever 110 adapted to swing from one end of the box to the other, and having a stud at one end pivotally shiftable in said wall slot and having a pivot pin connection adjacent the stud with the said block.

Signed at Seattle, King County, Washington, this 11th day of December, 1925.

ROBERT MILLS EVANS.
